No. 678,447.

Patented July 16, 1901.

M. O. WHELAN.

COPYING BATH.

(Application filed July 23, 1900.)

(No Model.)

UNITED STATES PATENT OFFICE.

MARTIN O. WHELAN, OF DETROIT, MICHIGAN.

COPYING-BATH.

SPECIFICATION forming part of Letters Patent No. 678,447, dated July 16, 1901.

Application filed July 23, 1900. Serial No. 24,484. (No model.)

To all whom it may concern:

Be it known that I, MARTIN O. WHELAN, a citizen of the United States of America, residing at Detroit, in the county of Wayne and 5 State of Michigan, have invented certain new and useful Improvements in Copying-Baths, of which the following is a specification, reference being had therein to the accompanying drawings.

10 The invention relates to new and useful improvements in baths for moistening copying cloths or blotters, and has for its object to produce a self-moistening pad having a source of water-supply, whereby it will be at 15 all times in readiness for use in wetting the cloths or blotters of the bath.

With this object in view, therefore, my invention consists of a pad in the form of a porous block having a reservoir for liquid-20 supply arranged therein and feeders leading from the reservoir to various parts of the pad, at which points the liquid is distributed throughout the entire block by means of capillary attraction.

25 The invention further consists in various other details of construction, as will be more fully hereinafter described, and shown in the accompanying drawings, in which—

Figure 1 is a perspective view of a frame-30 work constituting the mold in which the porous block is formed. Fig. 2 is a sectional view through the usual pan forming the body of the bath and through the pad arranged therein. Fig. 3 is a similar section through 35 a pad of modified construction. Fig. 4 is a plan view looking at the bottom thereof. Fig. 5 is a section on line $x-x$, Fig. 2, through one of the conduits as placed in the pad.

In the drawings thus briefly described the 40 framing referred to is designated by the letter A and comprises channel-shaped ends B, similar sides C, a hollow central member or reservoir D, and trough-shaped members E, which connect the central member with the 45 sides and ends, as shown. The hollow member D, which is preferably in the form of a metallic box, constitutes the reservoir for the pad, and in addition to a fill-opening F at its top is provided with a discharge-opening G, 50 formed in each of its sides. Tubes, such as H, form the conduits which distribute the water, and these are arranged, as shown, within the

troughs, their inner ends extending within the openings G. I may, however, dispense with the use of these tubes and simply lay 55 wicking in the troughs which act to feed the water to the absorbent as required. The framing or mold thus described is placed upon a flat surface and is filled with a soft or plastic composition which when dry forms a rigid 60 porous block. During the process of filling the material is packed tightly about the tubes and supports and over the reservoir, a core or plug being inserted within the fill-opening F to prevent the same from becoming ob- 65 structed. I also find it preferable to fill the reservoir D with waste or other absorbent matter to prevent the water from being fed too fast to the pad. The pad thus formed (shown in Figs. 1 and 2) is laid within the pan 70 I, which, as stated, constitutes the body of the bath. This pan is preferably of greater length than the pad, so that the socket K will be formed between one end of the pad and the pan, as shown. Within this socket the 75 cover L of the bath, which is preferably in the form of a block, can be conveniently supported in a vertical position while the blotters are being inserted or withdrawn from the bath, or the cover may be hinged to the pan, 80 as desired. The cover L has a metallic back- 85 ing L' and at its lower end is provided with a metallic facing K', adapted to strike against the end of the pad, and thus avoid all danger of injuring the composition lid in raising or lowering it, the weight of the cover being sufficient to press the blotters or cloths out smooth and exclude the air, so that the moisture will not be quickly carried off.

Figs. 3 and 4 illustrate a slightly-modified 90 construction in which the reservoir extends to the top of the pad and is provided with a suitable hinged cover, the V-shaped connecting troughs and conduits being dispensed with and the wicking or feeders simply laid in the 95 composition and radiating from the reservoir, the connecting-ribs M extending across the bottom of the frame to firmly unite the same and form supporting means for the reservoir and composition.

100 With my construction of metallic-bound pad I am enabled to manufacture these devices separate from the pan for use with any of the pans now in use. I also may, where the

complete pan is manufactured, dispense with the use of the metallic binding and mold the composition directly into the pan-body, the reservoir and its troughs or feeders having first been placed therein.

What I claim as my invention is—

1. A damping-pad for blotter-baths, consisting of a porous block having metal-bound sides and ends, a reservoir embedded centrally within the block, a multiple of tube-supports within said block connecting the reservoir with the metallic sides and ends, and tubes upon the supports communicating with the reservoir and extending therefrom to different parts of the block, substantially as and for the purpose described.
2. A blotter-bath, comprising a pan, a metallic-bound absorbent-composition block of a length less than the pan, having a flat top surface and placed in the pan, a reservoir embedded within said block, and means for gradually feeding the contents of said reservoir to the block, a metal cover for the pan, having a heavy absorbent filling that has a smooth surface, and is adapted to overlie the absorbent in the pan, and the cover and absorbent therein, adapted to stand on end in the vacant end of the pan.
3. A damping-pad for blotter-baths, consisting of a porous block, having metal-bound sides and ends, a reservoir embedded cen-

trally within the block, a multiple of V-shaped troughs within said block connecting the reservoir with the metallic sides and ends, and feeders within said troughs communicating with the reservoir and extending therefrom to different parts of the block, substantially as and for the purpose described.

4. A blotter-bath, comprising a pan, a metallic-bound absorbent-composition block having a flat top surface and removably laid in the pan, a reservoir embedded in said block, means for gradually feeding the contents of said reservoir to the block, a cover fitted to the pan and an absorbent composition having a flat surface combined with the cover for the purpose described.

5. A moistening-pad for blotter-baths composed of a rectangular metallic frame, connecting-rods uniting the opposite sides of the frame, a reservoir supported thereon centrally of the frame, an absorbent composition having a smooth surface surrounding said reservoir and contained within the frame, and means for slowly feeding the contents of the reservoir to the composition as required.

In testimony whereof I affix my signature in presence of two witnesses.

MARTIN O. WHELAN.
